UNITED STATES PATENT OFFICE.

RICHARD G. LEDIG, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

ELECTRIC HEATER.

1,415,660.

Specification of Letters Patent.

Patented May 9, 1922.

Application filed August 27, 1921. Serial No. 495,886.

To all whom it may concern:

Be it known that I, RICHARD G. LEDIG, a citizen of the United States, residing in Philadelphia, Pennsylvania, have invented 5 Electric Heaters, of which the following is a specification.

One object of this invention is to provide a relatively simple, compact and convenient device for electrically heating or melting 10 liquid or solid materials, which device shall be compact, ornamental and conveniently portable as well as inexpensive to make and operate.

These objects and other advantageous 15 ends I attain as hereinafter set forth, reference being had to the accompanying drawings, in which,

Fig. 1 is a central vertical section of an 20 electric heater constructed in accordance with my invention;

Fig. 2 is a plan of the heater shown in Fig. 1; and

Fig. 3 is a fragmentary vertical section on the line 3—3, Fig. 2.

25 In the above drawings 1—2 represents a two-part supporting frame of which the first part is a hollow, approximately frusto-conical casting designed to rest upon its basal portion and the second part is likewise 30 a hollow open frusto-conical structure having its basal portion uppermost, being, as shown in Fig. 3, rigidly connected to the portion 1 by screws 3. Between these two parts of the frame is clamped the flange of a 35 ring 4 and a plate in the form of a disc 5 of refractory non-conducting material centrally recessed for the reception of one end of a hollow cylinder 6 also of refractory substance, such as porcelain or other earth- 40 enware material.

The screws 3 which serve to clamp together the frame members and the bottom plate 5, also engage and hold an annular plate 7 against the top end of the cup 6 so 45 that the latter is immovably clamped in place. The plate 7 is at a level somewhat below the plane of the end of the top frame member 2 and is centrally cut away to provide an opening 8 into the cup 6 preferably 50 of the same diameter as the latter. An electrical heating element 9 in the form of a wire winding is mounted upon or embedded to a greater or less extent in the outer surface of the cup 6 and its two ends are carried out to a pair of terminals 10 and 11 in

the form of bolts carried by but electrically insulated from a metal supporting plate 12 whose edges are extended between and clamped in position by the upper end of the frame member 1 and the refractory base 60 plate 5.

Supply conductors 13 and 14 are electrically connected to the terminals 10 and 11 which are to some extent enclosed and protected by a circular metal plate 15 fitting 65 into the hollow base structure 1 and held thereto by screws of which one is indicated at 16. The cup formed by the base plate 5 and cylinder 6 has a bottom opening 17 for the admission of air and under conditions of 70 use the flow of current through the heating element 9 heats the walls of said cup to a high degree. Any structure mounted on the relatively flat top end of the frame member 2 or inserted within the cup is thus heated 75 by the hot air rising from and around said cup and this air is deflected or spread over the bottom of a structure on the frame member 2 by the annular plate 7 whose outer edge is spaced away from the inner walls of 80 said member 2 so that the air is free to pass upwardly around it as well as through its opening 8.

It is noted that both frame members 1 and 2 have vertically elongated openings 85 formed in their walls so that there is a free flow of air to and around the heating element which at the same time serves to keep said frame members themselves at a relatively low temperature. It is to be noted 90 that the base plate 5 of the heating cup extends outwardly beyond the heating element and the cylinder 6 on which it is mounted, so that it is engaged by the metallic elements 1 and 4 at some distance therefrom. Since said base plate is a relatively poor conductor of heat, this prevents objectionable conduction of heat from the cylinder 6 to the frame and insures the high heating of the air in the immediate vicinity of 100 the cup and its heating element as well as of the deflector plate 7.

I claim:

1. The combination in an electric heater of a frame including two hollow frusto-conical members; means for holding said members with their small diameter ends together; a refractory structure fixed within said frame; and a heating element wound on said structure. 105

2. The combination of a hollow frame; a hollow cylinder of refractory material mounted in said frame with its axis substantially vertical; and a heating element wound on said cylinder.
  3. The combination of a hollow frame; a hollow cylinder of refractory material; a heating element wound on said cylinder; a base plate fixed to the frame; and means 10 for clamping the cylinder to the base plate.
  4. The combination in an electric heater of a supporting frame; a base plate fixed thereto; a refractory structure mounted on said base plate; a winding mounted on said 15 refractory structure; with a plate connected to the frame and clamping said refractory structure to the base plate.
  5. The combination of a frame including
- two frusto-conical members; a base plate mounted between the smaller ends of said members; a heating element mounted on said base plate and extending upwardly therefrom within one of the frame members, said element including a winding; with terminals for said winding within the interior of 20 the second frame member.
6. The combination of an open work frame; a cup of refractory material mounted on said frame; and a heating winding for 25 said cup.
7. The combination of an open work frame; a refractory cup rigidly held within said frame with its opening adjacent the open top end of said frame; and a heating element wound on the cup.

RICHARD G. LEDIG.
